No. 772,795.

PATENTED OCT. 18, 1904.

N. A. FJELD.

FENCE POST.

APPLICATION FILED JULY 15, 1904.

NO MODEL.

UNITED STATES PATENT OFFICE.

NELS ANDERSON FJELD, OF JOICE, IOWA.

FENCE-POST.

SPECIFICATION forming part of Letters Patent No. 772,795, dated October 18, 1904.

Application filed July 15, 1904. Serial No. 216,712. (No model.)

To all whom it may concern:

Be it known that I, NELS ANDERSON FJELD, a citizen of the United States, and a resident of Joice, in the county of Worth and State of Iowa, have made certain new and useful Improvements in Fence-Posts, of which the following is a specification.

My invention is an improvement in posts designed especially for use as an anchor or corner-post for barb or woven wire fences; and the invention consists in certain novel constructions and combinations of parts, as will be hereinafter described and claimed.

In the drawings, Figure 1 is a side elevation of my post as in use and shown sunk in the ground. Figs. 2, 3, and 4 are respectively cross-sections on about lines 2 2, 3 3, and 4 4 of Fig. 1; and Fig. 5 is a detail perspective view showing the lower portion of the upright, together with the anchor-plate and the lower portion of the main strut-bar. Fig. 6 is an edge view of the post.

As shown, my post comprises the upright A, the main strut-bar B, the ground-rod C, a strut-brace D, a tension-bar E, and bolts F, connecting the tension-bar with the upright and having nuts f, which may be operated to take up slack by drawing the tension-bar toward the upright, as will be readily understood from Figs. 1 and 3 of the drawings.

The upright A, like the strut B, is made of channel-iron, and the upper end of the strut B is flattened at b and inserted in the channel of the upright A and secured by the bolt G, this form of connection operating in securing the alinement between the upright A and the strut B. At its lower end the upright A is provided with a foot a, which inclines downwardly and in the direction of the strut B and forms an inclined seat, upon which is secured the anchor-plate A', which presents a broad surface in the direction of the strut B, as shown in Figs. 1 and 5. At its lower end the strut B is bent, forming a foot B', projecting in a direction away from the upright A, and which in practice rests upon a rock H, as shown in Fig. 1 of the drawings. The ground-rod C is connected with the lower end of the upright A, preferably with the foot a, and extends thence upwardly and connects with

the strut B, near the foot B' thereof, thus connecting the anchor-plate with the lower end of the strut-bar. As the said ground-rod passes through the channel of the strut B, it aids in holding the lower end of the said strut 55 in proper alinement.

The upright A is provided with gate-hangers I, and a strut-brace D connects at its upper end with the upright A between the end b of the upright and the ground and extends 60 thence in a plane at a right angle to that of the strut B and bears at its lower end upon a rock h, suitably placed to form a foundation for the said brace-rod D, as shown in Fig. 1 of the drawings. This brace is used especially 65 in connection with a gate hung from the post to prevent the latter from leaning with the weight of the gate.

The tension-bar E has the wires J secured to it in any suitable manner, and this bar E 70 is connected with the upright A by the bolts F and nuts f, the bolts passing through the channel of the upright and the nuts operating to take up any slack that may occur from time to time.

In practice the parts of the post may be made of iron and will present a strong durable construction.

Having thus described my invention, what I claim as new, and desire to secure by Letters 80 Patent, is—

1. The improvement in fence-posts herein described comprising the upright of channel-iron provided at its lower end with an inclined foot and with an anchor-plate secured thereto, the main strut-bar of channel metal having its upper end flattened and secured with in the channel of the upright and its lower end forming a foot, a tension-bar for the connection of wires, bolts and nuts connecting 85 said tension-bar with the upright, the bolts extending through the channel of the upright, a brace-rod secured at its upper end to the upright below the connection of the main strut-bar therewith, and a ground-rod connecting 90 the lower end of the upright with the lower end of the main strut-bar, all substantially as and for the purposes set forth.

2. The combination in a fence-post, of the upright of channel metal provided at its lower 100

end with an inclined foot forming a seat for the anchor-plate, the anchor-plate held to said seat, and inclined to the vertical, the main strut-bar of channel-metal secured at its upper 5 end to the upright, said strut-bar and anchor-plate being approximately parallel, and the ground-rod connecting the lower end of the upright with the lower end of the main strut-bar and extending through the channels of 10 said upright and main strut-bar substantially as set forth.

3. The combination with the upright of channel-iron of the tension-bar for the connection of the wires, the bolts and nuts connecting 15 the tension-bar with the upright, the bolts extending through the channel of the upright and devices for bracing the upright substantially as set forth.

4. The combination of the upright of channel metal provided at its lower end with an inclined foot, an anchor-plate secured to said foot, a main strut-bar of channel metal flattened at its upper end and secured at said end within the channel of the upright, a ground- 20

rod connecting the lower end of the upright 25 with the lower end of the main strut-bar and passing through the channel of the latter, a tension-bar for the connection of the wires and bolts and nuts connecting the tension-bar with the upright, the bolts passing through the channel of the upright substantially as and for the purposes set forth.

5. The improvement in fence-posts herein described, comprising the upright having an inclined foot at its lower end, the main strut-bar secured at its upper end to the upright and inclining thence toward its lower end, the brace-plate secured to the inclined foot at the lower end of the upright and inclined at an angle approximately parallel to that of the 40 strut-bar, and a ground-rod connecting the inclined foot of the upright with the lower end of the main strut-bar, substantially as set forth.

NELS ANDERSON FJELD.
